UNITED STATES PATENT OFFICE.

WILBUR A. GAMBLE, OF WEST NEW YORK, NEW JERSEY, ASSIGNOR OF ONE-HALF TO
ROBERT J. HEITZMAN, OF UNION HILL, NEW JERSEY.

SKATE.

Application filed September 11, 1922. Serial No. 587,415.

To all whom it may concern:

Be it known that I, WILBUR A. GAMBLE, a citizen of the United States, residing at West New York, county of Hudson, State of New Jersey, have invented certain new and useful Improvements in Skates; and I do hereby declare the following to be a full, clear, and exact description of the invention, such as will enable others skilled in the art to which it appertains to make and use the same.

The invention relates to certain new and useful improvements in ice skates, and has for its object to provide a light, strong and durable skate that may be constructed of sheet metal at a minimum of labor and expense. To this end, the invention comprises a skate formed of two complementary body portions, preferably connected at intervals by spot welds, each body portion comprising a blade section, and integral upwardly and laterally extending ends, said blade sections and standards preferably being provided with reinforcing grooves pressed therein to form beads extending from the outer faces thereof, the body portions when suitably united serving to support light sheet metal sole and heel plates, which are secured to the laterally and outwardly extending ends of the standards. If desired, each of the blade sections may also have formed therein one half-section of a lubricant cup or holder, which communicates with the groove in the blade section, so that, when the several parts of the skate are assembled, a suitable lubricant placed in the cup or receptacle will work its way into the longitudinal channel formed by the mating grooves in the blade sections, and thence between the mating faces of the blade sections between the spot welds, to be ultimately delivered to the ice-engaging face of the blade.

The invention is illustrated in the accompanying drawings, in which:

Fig. 1 shows the skate in side elevation.

Fig. 2 is a plan view thereof;

Fig. 3 is a section on line 3—3, of Fig. 1.

Referring to the drawings, it will be noted that the skate comprises two complementary body portions preferably formed of pressed sheet metal, secured face to face, and a sole and heel plate secured to the two united body portions. Each of the body portions

comprises a blade section 1 having two standards 2, 2, located near its rear end, and three standards 4, 4, disposed toward its forward end, each of the standards being inclined outwardly, and terminating in a relatively flat outwardly and laterally extending perforated ear or end 3. Each of the standards 2 and 4 is also preferably provided with a groove 7, which is stamped or pressed in the inner face thereof to form an outwardly extending bead, which intersects the longitudinal bead 6 and the blade section 1. The reinforcing bead-forming grooves 6 and 7 impart the necessary element of strength to the two body portions of the skate to permit the latter to be stamped or cut from relatively thin sheet metal, but nevertheless to withstand the ordinary stresses incident to use, without distortion or deformation.

The two body portions, as thus constructed, are brought together face to face with the blade sections and standards in mating relation and the blade sections united at intervals, preferably by spot welding, although entirely satisfactory results may be obtained by connecting the blade sections together by rivets. When thus assembled, the corresponding standards 2 and 4 on each of the body portions constitute V-shaped supports, the outwardly and laterally extending ears of which are secured to the underfaces of a heel plate 8 and a sole or toe plate 10, which are provided with perforations 9 and 11 respectively, registering with the perforations in the ears 3 of the standards, the plates being secured to the ears of the standards by rivets 5 passing through the registering holes in the plates and ears aforesaid.

It has been found that, if the ice-engaging edge of a skate runner is lubricated, the speed of the skater may be greatly increased, and the energy required in the skating operation materially reduced. In order to provide a continuous supply of lubricant to the edge of the blade, a suitable receptacle for the lubricant is formed in the two blade sections by pressing a half cup section, as 15, in each of the blade sections, each half cup section communicating at its bottom with the longitudinal groove 6 in the blade section, so that, when the two blade sections are united, the two half cup

sections will register with each other and form a receptacle for a lubricant which is distributed throughout the length of the longitudinal channel formed by the mating grooves 6, and gradually seeps between the adjacent faces of the blade sections through the narrow openings between the spot welds. The lubricant cup is preferably closed by a suitable cap 16.

10 As thus constructed, it will be apparent that the complete skate is exceptionally light in weight, strong and durable in construction, and, as the several parts are made of relatively thin metal, stamped at a single 15 operation to ultimate form, the cost of material and labor is reduced to a minimum.

What I claim is:

1. A skate comprising two complementary body portions connected at intervals, 20 each comprising a half blade section, and integral laterally inclined standards having outwardly extending upper ends, said blade sections and standards having reinforcing beads formed therein extending 25 longitudinally and intermediate the edges thereof; and sole and heel plates secured to the ends of the standards.

2. A skate comprising two complementary body portions connected at intervals 30 by spot welds, each comprising a half blade section, and integral outwardly inclined standards having laterally extending ends, said blade sections and standards having reinforcing beads formed therein extending 35 longitudinally and intermediate the

edges thereof; and sole and heel plates secured to the ends of the standards.

3. A skate comprising two complementary body portions, each comprising a half blade section having a longitudinal reinforcing groove therein intermediate the edges thereof, and integral outwardly inclined grooved standards having outwardly and laterally extending ends; sole and heel plates secured to the ends of the standards; and means for securing the body portions together.

4. A skate comprising two complementary body portions connected together at intervals, each comprising a half blade section having a longitudinal groove on its inner face intermediate the edges thereof, and integral outwardly inclined standards terminating in outwardly and laterally extending ends; and sole and heel plates secured to the ends of the standards.

5. A skate comprising two complementary body portions connected together at intervals, each comprising a blade section having a longitudinal groove on its inner face and one half section of a lubricant holding cup on its inner face connecting with the corresponding groove, and integral outwardly inclined standards terminating in outwardly and laterally extending ends; and sole and heel plates secured to the ends of the standards.

In testimony whereof I affix my signature.

WILBUR A. GAMBLE.
